UNITED STATES PATENT OFFICE

2,287,694

ASH RECEIVER

Edward F. McDonald, Buffalo, N. Y., assignor to
McDonald Products Corporation, Buffalo, N. Y.

Application September 29, 1939, Serial No. 297,018

2 Claims. (Cl. 131—241)

This invention relates to improvements in ash receivers.

The present invention provides an improved construction for an ash receiver and floor stand, in which a receptacle open at the upper end carries a rim that extends outwardly therefrom formed at the outer edge with a depending flange cooperating with the rim to form a rigid handle structure, for carrying the stand when it is desired to move it from place to place. The rim further provides a support about the receptacle for receiving a cigarette and the like in transversely extending relation with one end projecting into the open upper end of the receptacle, the rim preferably being formed so that it will incline upwardly from the inner edge toward the outer edge with a slight curvature. This incline and curvature normally causes a cigarette or similar article laid on the rim to roll or gravitate toward the opening in the receptacle. This arrangement will support a cigarette or the like in transversely extending relation only with one end projecting inwardly over the open upper end of the receptacle. If the receiver or stand is jarred or moved, a cigarette on the rim will gravitate, slide or roll toward the receptacle.

The invention provides a rim structure for ash receivers in which the rim is constructed to provide a rest for cigarettes and the like and at the same time has a depending flange portion on the outer edge cooperating with the rim to form a handle structure by which the receiver or stand may be carried about.

The invention further comprehends the provision of a flange on the inner edge of the rim formed to provide a seat to support an ash container so it may be removably suspended from the seat in the receptacle. An outwardly extending flange on the upper edge of the receptacle also cooperates with the rim to retain the shape of the rim against deformation.

The invention also comprehends the provision of an ash receiver in which the receptacle carries a rim extending outwardly therefrom arranged to have an upwardly inclined portion toward the outer edge of the rim formed with a depending flange to provide a handle for carrying the receiver while the inner edge of the rim is arranged to detachably receive and suspend therein a suitable ash container having the upper edge arranged in substantially the same plane as the inner edge of the rim to cause a cigarette or the like mounted thereon in transversely extending relation to gravitate toward the ash container, the rim cooperating to arrest this inward motion to

some extent in order to support the cigarette and the like with the inner end overhanging the opening in the container in a manner convenient for the further handling of the cigarette.

In the drawing:

Fig. 1 is a side elevation of the upper end of a floor stand ash receiver construction with portions broken away and shown in cross section to clearly disclose the details of construction.

Fig. 2 is a view taken on line 2—2 of Fig. 1 looking upwardly at the bottom of the receptacle and rim structure.

The term ash receiver used herein is intended to include an ash receiver that is adapted to set on a table or the like including either an open or closed receptacle construction, as well as the type of construction generally known as a floor stand, in which a suitable pedestal is provided for supporting the ash container at an elevation above the floor. In the form of the invention illustrated, it is shown as applied to a floor stand structure in which the pedestal is indicated at 1 and is formed in any suitable manner well-known in the art which may be carried by an appropriate type of base construction, not shown.

A receptacle 2 is mounted on the upper end of pedestal 1, and in the form illustrated, it is cylindrical, closed at the bottom and has an open upper end. The sides of receptacle 2 at the upper end are formed with an annular outwardly extending flange 3.

A rim 4 of annular form is provided at the inner edge with a downwardly extending annular flange 5 offset inwardly at 6 to form a seat, the lower portion of the flange extending downwardly from the seat and receiving suitable attaching means indicated at 7 for securing the rim to the receptacle. The outer edge of rim 4 is formed with a depending annular flange 8 having a return bend portion 9. Flange 8 cooperates with the adjacent rim structure to provide a handle for carrying the receptacle or stand.

As illustrated in Fig. 1 the rim between flanges 5 and 8 is seated on the upper surface of flange 3 and is curved upwardly in outward or radial relation from the receptacle so that the juncture of the rim with flange 8 at its outer edge or periphery is higher than at the inner edge. This provides an inclined substantially conoidal surface in which the incline throughout the rim is inwardly toward receptacle 2, the shape of the surface not being truly conical because of the curvature between the outer and inner edges of the rim, as illustrated in Fig. 1. Rim 4 is substantially narrow compared with the diameter

across the outer periphery thereof, that is, it is somewhat less than the length of the usual cigarette as illustrated in Fig. 1.

A suitable container 10 for ashes and other refuse is provided with a detachable top member 11 of annular form having a central opening, not fully shown. The outer periphery of rim 11 is adapted to engage an offset seat portion 6 at the lower end of flange 5 for supporting container 10 in suspended position, as shown in Fig. 1, within receptacle 2. The upper edge of the container or top 11 thereof is arranged in substantially the same horizontal plane with the inner edge of rim 4, as illustrated in Fig. 1, so the inner end of a cigarette or the like, supported on the receiver in the manner disclosed in Fig. 1, will project into the opening in the container. The inclination and curvature of rim 4, as disclosed in Fig. 1, is designed with the particular purpose of preventing a cigarette from being supported on rim 4 in any position except a substantially transversely extending position as illustrated in Fig. 1.

In other positions, a cigarette or the like of general cylindrical form will roll inwardly toward container 10 and will either roll into and through the opening in top 11 or onto the flat top surface of top 11 immediately adjacent to rim 4. This tends to prevent a lighted cigar, cigarette or the like from being placed on rim 4 in such a manner that it is likely to roll off, be jarred off, or due to the constant burning of a cigarette, have the end overbalance and drop off the outer edge. In the present construction the tendency of a cigarette or the like when it is mounted in transversely extending relation on rim 4 as shown in Fig. 1 is to gravitate inwardly toward container 10. The inclination is such that a cigarette or the like may be placed in the position as indicated in Fig. 1 in the drawing where it will remain so long as the receptacle and rim is not jarred or moved. The jarrring or movement of the receptacle and rim 4 will immediately, due to the inclination between the outer and inner edges of rim 4, cause the cigarette to slide inwardly into container 10. This effectively guards against lighted cigarettes or the like falling on the floor off of rim 4.

In cases where condensation wets the paper covering of the cigarette positioned as shown in Fig. 1, the cigarette will then have a tendency to stick to rim 4 and cover 11. It has been found that the cigarette will burn out before a sufficient length of the cigarette burns to allow the end, as shown in Fig. 1, to drop off of the outer edge of rim 4.

Any suitable type of container may be used for suspension in seat 6 of rim 4, the type shown including a covered type of ash container, although it will be understood that an open type of container may be used in place thereof. Receptacle 2 may also be utilized as the ash receiver, if desired, by either omitting the use of the container or by utilizing a top member similar to that shown at 11 engaged in seat 6 without having the remainder of the container structure so that refuse and ashes will be directly contained within receptacle 2. This last described variation of the invention is not desirable because where the receptacle is carried as part of a floor stand structure, it is more difficult to keep the refuse cleaned out of the receptacle.

For that reason it is preferred to use a removable container for receiving the ashes and other refuse that can be detachably engaged in and suspended in receptacle 2 from seat 6.

5 The invention claimed is:

1. An ash receiver comprising a receptacle open at the upper end, a narrow rim having an imperforate supporting section normally positioned in substantially horizontal relation but having the surface slightly inclined to position the outer edge slightly above the inner edge, a depending annular flange on the inner edge of said section slidably engaged in the upper end of said receptacle with the under face of said section adjacent said flange seated on the upper edge of said receptacle, said flange having the lower end portion offset inwardly in spaced annular relation to the inner wall of said receptacle, said offset forming a seat below the upper edge 10 in said receptacle, means securing said receptacle to said flange, an ash container formed to slidably fit in said annular flange and engage said seat with the upper edge substantially aligned with the upper surface of said section and the bottom portion suspended in said receptacle from said seat in spaced relation to the walls of said receptacle, and an annular flange depending from the outer edge of said section extending below the bottom face of said section and cooperating 15 to form an annular handle for said ash receiver while said section will normally support a cigarette, or the like in transversely extending relation at any part of its surface when at rest thereon but will cause a cigarette in motion relative thereto and in other than a substantially transverse position to roll or slide inwardly toward said container.

2. An ash receiver comprising a receptacle open at the upper end and having an annular 20 laterally and outwardly extending flange on said upper end, a narrow rim having the lower inner marginal face seated on the upper face of said flange, a depending annular flange on the inner edge of said rim extending into the upper end 25 of said receptacle in engagement with the inner face of the side wall thereof, means securing said flange to said receptacle, said depending flange having the lower end portion offset inwardly in annular relation to provide a seat below the upper edge of said receptacle with said end portion spaced inwardly from the walls of said receptacle, an outer annular depending flange on the outer edge of said rim extending below the bottom face of said rim and forming 30 a carrying handle for said ash receiver, said rim having the entire area thereof between said inner and outer depending flanges forming an annular supporting section having a uniform surface configuration extending in substantially horizontal relation but in slightly curved and upwardly inclined relation from the inner to the outer flange for normally supporting a cigarette or the like thereon in a position of rest in transversely extending relation, and normally causing 35 a cigarette to move thereon toward said receptacle when a cigarette or the like is placed thereon in other than a substantially transversely extending position, and said seat forming a support for an ash container suspended therefrom in said receptacle through the lower end portion of said inner depending flange.

EDWARD F. McDONALD.
